ADJUSTABLE MACHINE-TOOL VISE

BACKGROUND OF THE INVENTION

Heretofore the vise jaws have required a means for effecting the vertical adjustment of the working position with a separate means for effecting the horizontal adjustment of the working position. The disadvantage of such structures are numerous.

DESCRIPTION OF THE INVENTION

The invention has for its object a vise in which the means of the jaws can be rotated horizontally or vertically through 360° to any desired working position.

A further object is to provide this type of vise with jaw sections slidable within each other and operated by a single center spindle and arranged so that by removing a small section at one end of the vise, the complete unit can be dismantled from its base support, which support, thereupon, can be used as a separate clamping device for tools, etc., and the top of which device can be used as an anvil.

Further objects and features of the invention will be apparent from the following detailed description when taken in connection with the accompanying drawings, in which:

FIG. 1 is a cross-sectional view of a horizontally and vertically adjustable machine-tool vise according to the invention;

FIG. 2 shows a section of the vise taken along the line 2-2 of FIG. 1 and illustrating the means for holding and adjusting the jaw sections;

FIG. 3 is a section of the vise taken along the line 3-3 of FIG. 1 and showing the means for locking these sections;

FIG. 4 is a plan view of the jaw sections and clamping means for holding same; and

FIG. 5 is a plan view of the base support rotatably mounting the arrangement of FIG. 4, and, the key means for locking and unlocking same in any vertical and horizontal position.

Referring now to the drawings in which like numerals designate like parts, the embodiment shown in FIG. 1 comprises a base plate 1 with a central bore 2 in which a substantially cylindrical, split stud 3, FIGS. 2, 3 and 4, is rotatably mounted. The stud 3 which projects downwardly from a C-shaped clamp 4, FIG. 4, consists of two joinable halves 3a and 3b, respectively, which are arranged such that each half is integrally formed with one free end, 4a and 4b respectively, FIG. 4, of the C-clamp 4 and such, that upon joining or drawing together of these two stud sections, the free ends of the clamp are correspondingly drawn together.

The clamp 4 arranged with a central bore 5, adapted to engage and hold the vise arrangement 6, at its upper part is formed into a plane which suitably serves as an anvil, 4c, and, at its lower side is formed with its two free ends 4a and 4b.

Projecting upwardly from the base 1 and engaging the stud 3 is a hub 7 provided with a first cylindrical bore 8 which extends coaxially with the baseplate bore 2 and with a second cylindrical bore 9 which laterally and transversely intersects the bore 8 through a small arc, as clearly shown in FIG. 3.

Formed at the intersection of the first bore 8 and the second bore 9 and extending transversely relative to the longitudinal axis of the bore 8, is a substantially elliptical recess 10, FIG. 5, formed through the walls of these bores via which recess a first and a second clamping pieces 11 and 12 movably arranged inside the bore 9, actively engage and compress the stud sections 3a and 3b under actuation of a clamping screw 13 rotatably journaled through these clamping pieces.

As can be seen from FIG. 5, these clamping pieces, 11, 12, in the form of bushings are adapted to be coaxially arranged inside the bore 9 adjacent each other and disposed to be drawn and joined together by the clamping screw 13; to this extent, the outer piece 12 is arranged with inner threads which mesh with outer threads on the screw 13. Sandwiched between the outer piece 12 and a shoulder portion 14 of the screw 13, is the second piece 11 and, journaled through the shoulder portion 13 is a crank 15 disposed to actuate the screw 13, in a manner known per se.

As shown in FIG. 5, the inner opposite ends of the clamping pieces 11 and 12 are chamfered such that when drawn together, a substantially oval and concave recess is formed, the concave contour of which corresponds to and laterally engages the exterior of the stud halves 3a and 3b thereby compressing same and locking the stud 3 firmly inside the hub 7 and, at the same time, locking the vise arrangement 6 inside the clamp 4.

Arranged circumferentially in the exterior of the stud 3 is a groove 16 disposed to permit free passage of the screw 13 through that section of the stud adjacent the intersection of the first and second bore, 8 and 9, respectively.

Rotatably and lengthwise movably arranged in the C-clamp 4, is the vise arrangement 6, consisting of a fixed jaw section 17 and a jaw section 18 movable relative to the section 17. The jaw section 17 is seen to comprise a first jaw 19 integrally formed with and enclosing a guide tube 20 adapted to slidably receive a sliding tube 21 enclosed by and integrally formed with a second jaw 22.

A key and keyway 20a is provided between the guide tube 20 and sliding tube 21 inserted therein, to ensure longitudinal movement of the sliding tube and to prevent rotary movement thereof.

Extending longitudinally inside the sliding tube 21 is a screw spindle 23 which at its operated side is connected via an opening 24 arranged in the jaw 22, to a crank 25 journaled through a shoulder portion 26 of the screw 23 at the outer end of the jaw 22.

Sandwiched between the shoulder portion 26 and the outer surface 27 of the jaw 22 is a connector disc 28 integrally formed with the shoulder portion 26 and adapted, via the screw connections 29, to detachably position the spindle 23 inside the sliding tube 21.

Nutwise and fixedly positioned inside the tube 21 is a spindle guide in the form of a third tube 30 rigidly connected at its inoperative end 31 to a circular connector cap 32 enclosing the outer end 31 of the tube 20 and detachably connected thereto via the screw connections 33.

The spindle guide 30 is arranged with inner threads 34 meshing with outer threads 35 of the spindle 23 to permit same to be turned in and out so as to increase or decrease the width between the two jaws, 19 and 22.

Upon loosening of the screws 33, the spindle guide 30 can be completely turned out and detached from the spindle 23, thereby rendering the vise arrangement 6 completely detachable from the C-clamp 4 after loosening of the clamping screw 13.

It will be understood from the foregoing that, upon positioning of the vise arrangement 6 in the C-clamp 4 in any desired vertical position within a range of 360° and, upon positioning of the stud 3 in the hub 7 in any suitable horizontal position within a range of 360°, the clamping screw 13 actuated by the crank 15, draws the clamping pieces 11 and 12 into engaging contact with the stud halves 3a and 3b thereby tightening and securing the latter against rotation in the hub 7, as a result of which the vise arrangement 6 loosely positioned in the C-clamp 4, is tightened and locked against rotation within the clamp.

I claim:

1. In a position adjustable tool vise having a fixed jaw section with an axially horizontal extending guide tube, a movable jaw section with a sliding tube inserted in said guide tube for longitudinal movement therein and, a screw spindle inside said tubes for moving said moving section relative to said fixed section, wherein the improvement comprises:

a. a base plate for mounting said sections and having a central orifice;

b. a support clamp having a central bore adjustably enclosing part of said guide tube and, having its free ends formed into parallel projections rotatably mounted in said central orifice;

c. clamping means arranged on said base plate and peripherally engaging said projections, whereby upon

- tightening of said clamping means said support clamp is secured against rotation on said base plate and said guide tube is held against rotation within said support clamp;
- d. a key and keyway are arranged between said guide tube and said sliding tube to ensure longitudinal movement of the latter inside said guide tube and to prevent rotary movement of same;
- e. said screw spindle being provided with outer threads meshing with inner threads arranged at one end of a bore of an elongated spindle support tube disposed lengthwise inside said sliding and guide tube;
- f. said support clamp having a C-shaped, configuration and said parallel projections being formed by two compressible stud sections, each section of said stud being integrally formed with one free end of said C-shaped clamp 15 so that upon joining of these two stud sections, said free ends of said clamp are correspondingly drawn together, the upper section of said C-clamp is formed into a plane to form an anvil;
- g. said clamping means having a cylindrical hub having a first central bore extending coaxially with said central orifice in said base plate, a second bore laterally intersecting said first bore through a small arc and, clamping pieces arranged in said second bore and actuated by a clamping screw for peripherally engaging and projections.
2. A tool vise according to claim 1, wherein said second bore transversely intersects said first central bore and opens

therein through a substantially elongated recess arranged in the walls of said bores to permit clamping engagement of said clamping pieces with said stud sections through said recess.

3. A tool vise according to claim 1, wherein at the transverse intersection of said first and second bore a groove is arranged circumferentially in the exterior of said stud sections to permit free passage of said screw through that section of the stud sections adjacent the intersection of said first and second bore.
- 5 4. A tool vise according to claim 2, wherein said clamping pieces are in the form of two adjacent and axially aligned bushings movably and detachably arranged inside said second bore and drawn together by said clamping screw into clamping engagement with said stud sections.
5. A tool vise according to claim 4, wherein the inner adjoining ends of said clamping pieces are chamfered and form a curved recess corresponding and cooperating with the exterior of said stud sections.
6. A tool vise according to claim 4, wherein said pieces have a central passage in which said clamping screw is rotatably journaled and, wherein one of said pieces is arranged with inner threads meshing with the outer threads of said screw and, the second of said pieces is sandwiched between said first piece and a shoulder portion of said screw and, means for turning said screw to draw said pieces together.
